PORTABLE BATTERY OPERATED
FLUORESCENT HAND LANTERN

Jesse A. Barr, Highland Park, Calif.

Application January 27, 1947, Serial No. 724,557

3 Claims. (Cl. 248--16.63)

1

This invention relates generally to portable, battery operated, electrical hand lanterns.

It is an object of this invention to provide a new and improved battery operated hand lantern utilizing a fluorescent electric lamp as the light source, and it is a particular object to provide a lamp construction in which the fluorescent lamp is mounted vertically in a manner to throw light through 360°.

It is also an object of the invention to provide an attractive electric hand lantern of simple construction in which it is easy to change or replace the lamp and the batteries.

These and other objects will be apparent from the drawing and the following description. Referring to the drawing, which is for illustrative purposes only:

Fig. 1 is an elevational view of a lantern embodying the invention;

Fig. 2 is a vertical sectional view on an enlarged scale of the device of Fig. 1;

Fig. 3 is a sectional plan view on line 3--3 of Fig. 1;

Fig. 4 is a sectional plan view on line 4--4 of Fig. 1;

Fig. 5 is a sectional plan view on line 5--5 of Fig. 1;

Fig. 6 is a fragmentary perspective view of a portion of the lamp supporting plate at the upper end of the lamp; and

Fig. 7 is a perspective view of one lamp socket member.

More particularly describing the invention, reference numeral 10 generally indicates the base of the lamp. This base is in the form of a hollow casing and comprises an upper section 11 and a lower section 12 adapted to fit therein and be secured thereto in any suitable manner, as by means of screws 13. Preferably the base is cylindrical, although it might conceivably take other shapes. The base may be made of sheet metal, plastic or other suitable material.

Extending upwardly from the base are a pair of hollow tubes 15 which are threaded at their ends so that they may be readily secured in place as by means of the nuts 16 shown securing the tubes to the upper wall 18 of the base through which they extend. The tubes 15 have a dual function in that they support the upper structure of the lamp and also serve as conduit means for housing the wires which must necessarily extend to the upper portion of the fluorescent lamp tube 19. These tubes support a plate 22 through which they extend and are securely fastened thereto by means of nuts 18.

The plate is provided with an upturned peripheral flange 23 about which fits a domed cover 25. These two parts are held together by means of a handle or bail 26, the ends 27 of which extend through registering holes 28 in the cover and the flange 23 of plate 22 (Fig. 3). With this construction the cover may be readily removed from the remainder of the lamp when desired.

The plate 22 is provided with a central recessed portion 29 on its under surface and the upper wall 18 of the base is similarly shaped or dished to provide a recess 31. A cylindrical globe 32 is mounted between these parts, the globe fitting within the aforementioned recesses 29 and 31 at the peripheral portions thereof.

The upper wall 18 of the casing and the plate 22 are each centrally apertured at 33 and 35, respectively, to accommodate the ends of the fluorescent tube 19. The plate and the casing wall each have a projecting apertured lug 37 upon which is mounted a lamp socket generally indicated by 38, the lamp socket having an apertured projecting mounting plate 39 through which rivets 40 extend. Preferably the central opening 35 in the plate is large enough to permit of the removal of the lamp tube through that opening so that the same may be changed readily.

The base 10 is adapted to accommodate a starter and switch mechanism 42 including a starter button 43 and an "off" button 44, which project through the wall of the base. The starter has been schematically shown and may consist of any conventional electrical means, as is commonly employed to provide a sufficient charge to initially light the lamp.

The base accommodates one or more batteries 46. These batteries are connected in any ordinary way to the starter and switch mechanism 42, and wires are run to the two lamp sockets. As previously pointed out, the wires 47 and 48 to the upper socket run through the supporting tubes 15. It is, of course, contemplated that both wires could be run through a single hollow tube and a solid rod might replace the other hollow tube.

With the construction described, it will be apparent that an attractive lantern of simple construction has been provided. The batteries may be replaced by removing screws 13 to release the casing section 12. The lamp tube may be installed and removed through the opening 35 in the plate 22. For this operation, it is only necessary to first remove the cover 25 by expand-

ing the ends of the handle to remove them from the cover and release the same.

While the invention has been particularly shown and described, it is contemplated that various changes and modifications can be made without departing from the scope thereof as set forth in the accompanying claims.

I claim:

1. A portable hand lantern comprising a base formed of a circular hollow casing means adapted to contain a battery, said casing having a centrally apertured upper wall dished to form a recess surrounding the aperture, a pair of upright supports mounted on said base, a plate inclosed on said supports at the upper ends thereof, said plate being centrally apertured and having a recess similar to that of said upper wall of said base, a lamp socket supported by said plate behind the central aperture therethrough and a second lamp socket supported by the upper wall of said casing behind the central aperture therethrough, a lamp tube extending vertically between said sockets, said aperture in said plate being of sufficient size to permit of the removal therethrough of said lamp tube past said socket, and a light transmitting globe extending between said base and said plate enclosing said lamp tube.

2. A portable hand lantern comprising a base formed of a circular hollow casing means adapted to contain a battery, said casing having a centrally apertured upper wall dished to form a recess surrounding the aperture, a pair of upright tubes mounted on said base, a plate mounted on said tubes at the upper ends thereof, said plate being centrally apertured and having a recess similar to that of said upper wall of said base, a lamp socket supported by said plate behind the central aperture therethrough and a second lamp socket supported by the upper wall of said casing behind the central aperture therethrough, a lamp tube extending vertically between said sockets, said aperture in said plate being of sufficient size to permit of the removal

therethrough of said lamp tube past said socket, said tubes being adapted to act as wire conduits for wires extending from said base to the lamp socket mounted on said plate.

3. A portable hand lantern comprising a hollow casing adapted to contain a battery and to form a base, said casing having a single-piece upper wall formed with a centrally recessed upper surface and with an opening in the recessed surface, a pair of upright supports mounted on said base, a plate of substantially the same size as said upper wall of said casing mounted at the upper ends of said supports, said plate being recessed on its under surface to correspond to said recessed upper surface of the upper wall of said casing and having an opening in the recessed surface aligned with the opening in said upper wall, a lamp socket supported by said upper wall behind the opening therein and a lamp socket supported by said plate behind the opening therein, and a tubular light transmitting globe extending between said plate and said upper wall of said casing, said globe fitting within the recesses of said plate and said upper wall of said casing.
